OF CHESTNUT HILL, MASSACHUSETTS.

HANDLE ATTACHMENT.

1,095,873.

Specification of Letters Patent.

Patented May 5, 1914.

Application filed June 10, 1913. Serial No. 772,812.

To all whom it may concern:

Be it known that I, WADE H. JAYNE, a citizen of the United States, and a resident of New York, borough of Manhattan, in the 5 county and State of New York, have invented a new and Improved Handle Attachment, of which the following is a full, clear, and exact description.

My invention relates to improvements in 10 handle attachments, and has reference more particularly to handles removably associated with a brush, or similar article, the top of which article is also removable.

An object of the invention is to provide a 15 simple and inexpensive adjustable handle attachment for brushes, or similar articles, which handle can be used for different articles provided with means for engaging the handle.

20 Another object of the invention is to provide a handle attachment which is removably and adjustably associated with the top of a brush or a similar article.

The invention consists of the construction 25 and combination of parts to be more fully described hereinafter and fully set forth in the claims.

Reference is to be had to the accompanying drawings forming a part of this specification, in which like characters indicate corresponding parts in all the views and in which:

Figure 1 is a plan view of a brush embodying my invention; Fig. 2 is a longitudinal section on line 2—2, Fig. 1; Fig. 3 is a cross section on line 3—3, Fig. 1; Fig. 4 is a section on line 4—4, Fig. 3; and Fig. 5 is a perspective view of the nut carrier before the same is made to engage the nut.

40 Referring to the drawings, 6 represents the bristles of a brush secured in a member 7 forming the bristles holder. The member 7 is provided with bolts 8, preferably removable from same, and adapted to engage the 45 top 9 of the brush, which is rigidly secured to the member 7 by means of winged nuts 10 engaging the bolts 8 and pressing against washers 11 provided on the upper surface of the brush top 9. The brush top preferably 50 has, in cross section, the shape of a circular segment the base of which is substantially equal in width to the width of the bristles holder 7. A central raised portion 12 is provided on the curved surface of the top 9, and 55 in this raised portion a central recess 13 is

formed; see Figs. 2, 3 and 4. The bottom of the recess 13 is preferably concentric with the curved surface of the top, so as not to reduce unnecessarily the strength of the top in the center.

60 Fitting over the recess 13 is a slotted guide member 14, the slot 15 of which is in alignment with the recess 13. The guide member 14 fitting over the curved surface of the raised portion 12 covers entirely the recess 13 and is secured to the raised portion 12 of the top 9 by means of screws or any other suitable means. The ends of the guide member 14 are preferably extending slightly over the base of the top 9 so as to engage the sides 70 of the bristles holder 7, thereby helping the bolts 8 to maintain the top 9 and the bristle holder 7 in alignment with each other.

Associated with the guide member 14 is a 75 nut carrier 16 the flange portion of which is provided with a central opening 17, and with a pair of parallel central arms 18, each forming the continuation of a side of the flange, which is preferably of rectangular form. The arms 18 of the nut carrier 16 fit 80 snugly into the slot 15 of the guide member 14 with the flange resting on the top surface of the guide member 14. The face of the nut carrier contacting with the guide member 14 is provided with raised edges 19 85 which are adjacent to the arms 18, and which raised edges, in combination with the central portion of the flange, form contact points between the flange of the nut carrier 16 and the surface of the guide member 14. 90

The arms 18 projecting into the recess 13 receive the nut 20 which has its threaded opening in alignment with the opening 17 of the flange of the nut holder; and the width of the nut is preferably equal to the 95 width of the recess, so that the same cannot turn in the recess. Furthermore, the distance between the arms 18 is also equal to the width of the nut, so that it cannot turn between the arms 18. The ends of the arms 100 18, after receiving the nut between them, are bent toward each other (see Fig. 3), so as to maintain the nut against the inner curved surface of the guide member 14. When the ends of the arms 18 are bent, as 105 shown in Fig. 3, the nut becomes a part of the nut carrier 16 and follows the motion of the same, the nut carrier being guided in its motion by the arms 18 in the groove 15, and is prevented from being pulled out of 110

the groove by the nut 20 engaged by the ends of the arms 18. A handle 21 is provided with a threaded stud 22 which fits into the nut 20, whereby the handle is attached to the top of the brush. When the stud 22 is screwed into the nut 20 it forces the nut against the inner curved surface of the guide member 14; and the flange of the nut carrier is carried against the upper surface of the said member, thereby locking the carrier and the nut against the guide member 14. When the stud 22 is loosened from the nut by means of the handle the nut carrier can be moved in the groove 15 of the guide member 14 and thereby the handle may be placed at any desired position with reference to the top 9 within the limits permitted by the groove 15 provided in the guide member 14.

With a brush as described, the top can be used with different bristle holders. As, for example, brushes for dirty and clean work can be used with the same top; or, when a brush is worn out, a new bristles holder can be secured to the old brush top by a simple manipulation of the bolts 8. This provision not only gives a perfectly adjustable handle but it saves the expense of brush tops, which is not to be neglected where a large number of brushes is used.

Having thus described my invention, what I claim as new and desire to secure by Letters Patent is:

1. The combination with a brush top having a recess of a handle attachment comprising a nut in the recess; a guide member having a slot and inclosing the nut in the recess; a member resting on the guide member and having means passing through the slot and engaging the nut, whereby the nut is carried; and a handle having a threaded stud adapted to engage the nut for the purpose set forth.

2. The combination with a brush top having a recess of a handle attachment comprising a nut in said recess; a carrier for said nut; a guide for said nut carrier se-

cured to the said top; and a handle having a threaded stud adapted to engage the nut whereby the handle, nut and nut carrier can be locked to the guide.

3. The combination with a brush top having a transverse recess of a handle attachment comprising a slotted member over said recess; a nut in said recess; a nut carrier having a flange portion resting on the slotted member and having arms extending through the slot and engaging the nut in the recess, said flange having a central opening in alignment with the nut opening; and a handle having a threaded end adapted to pass through the opening of the flange and engage the nut, whereby the handle, nut and nut carrier may be locked at any desired position of the slotted member.

4. The combination with a brush, or similar article, having a top provided with a recess therein of a handle attachment comprising, a locking member in said recess; a guide inclosing the locking member in the recess; a carrier for said locking member engaging said guide; and a handle having means adapted to engage the locking member and whereby the handle is locked to said guide, substantially as and for the purpose set forth.

5. The combination with a brush top having a recess of a handle attachment comprising a locking member in said recess; a carrier for the locking member; a guide for the carrier secured to the top; and a handle having means adapted to engage the locking member and the guide and whereby the handle, locking member and carrier are locked to the guide, substantially as and for the purpose set forth.

In testimony, whereof I have signed my name to this specification in the presence of two subscribing witnesses.

WADE H. JAYNE.
